UNITED STATES PATENT OFFICE

1,960,384

FIRE EXTINGUISHER

Jack Lincoln, Niagara Falls, N. Y.

Application February 19, 1934, Serial No. 712,039

2 Claims. (Cl. 169—2)

The present invention relates to new and useful improvements in fire extinguishers particularly for motion picture projecting machines and has for its primary object to provide, in a manner as hereinafter set forth, a novel construction, combination and arrangement of parts for expeditiously extinguishing a fire in either or both of the magazines of the machine.

Another very important object of the invention is to provide a fire extinguishing apparatus of the aforementioned character embodying novel means for automatically closing and maintaining in closed position the doors of the magazines.

Other objects of the invention are to provide a fire extinguisher for motion picture projecting machines which will be comparatively simple in construction, strong, durable, highly efficient and reliable in operation, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in side elevation, showing the upper and lower magazines of a motion picture projecting machine equipped with a fire extinguishing apparatus in accordance with the present invention.

Figure 2 is a plan view, showing the means for automatically closing the magazine doors.

Figure 3 is a view in horizontal section, taken substantially on the line 3—3 of Figure 1 but showing the magazine door in open position.

Figure 4 is a vertical sectional view, taken substantially on the line 4—4 of Figure 3.

Figure 5 is a fragmentary view in bottom plan of a portion of the discharge pipe which is mounted in the upper magazine.

Figure 6 is a detail view in top plan of the discharge pipe which is mounted in the lower magazine.

Referring now to the drawings in detail, it will be seen that the reference numeral 1 designates generally the usual head of a motion picture projecting machine above which is mounted the upper magazine 2 and below which is mounted the lower magazine 3. The doors 4 of the magazines 2 and 3 are secured in position through the medium of hinges 5, the portion of each hinge 5 to which the doors are secured having fixed thereon a cam 6 the purpose of which will be presently set forth.

Mounted transversely on the fronts of the magazines 2 and 3, adjacent the hinges 5, are horizontal cylinders 7 having connected to one end thereof fluid supply pipes 8 from a suitable source. The supply pipes 8 are to be controlled by suitable valves (not shown) located at a convenient point in the booth. Rods 9 extend slidably into the cylinders 7 through the other ends thereof and have fixed on their inner ends pistons 10. Rollers 11 are journaled on the outer ends of the piston rods 9 for operative engagement with the cams 6.

The cylinders 7 are mounted in position through the medium of laterally projecting nipples 12 which extend into the magazines 2 and 3. 70 Mounted in the upper portion of the magazine 2 and connected to the corresponding nipple 12 is an endless, perforated discharge pipe 13 which, as best seen in Figure 1 of the drawings, is arcuate in side elevation to conform to the curvature of 75 the magazine. A perforated discharge pipe 14 is mounted in the lower magazine 3, said discharge pipe 14 having a gap 15 therein for the passage of the film into said lower magazine.

Attention is here invited to the fact that the 80 ports 16 in the cylinders 7 provided by the nipples 12 are controlled by the pistons 10. In operation, should a fire occur in either or both of the magazines 2 and 3 the valves in the supply pipes 8 are opened for admitting fluid under 85 pressure to the cylinders 7. When the fluid enters the cylinders 7 the pistons 10 are actuated thereby in a direction to close the magazine doors 4, said pistons being moved past the outlet ports 16 provided by the nipples 12 for permitting the 90 extinguishing fluid to enter the perforated pipes 14 and 15 to be discharged into the magazines. Should the doors 4 be forced open by explosions 95 in the magazines or from any other cause, said doors will be immediately closed again by the fluid pressure in the cylinders 7, as is believed to be apparent. In Figure 1 of the drawings the front wall of the booth is designated by the reference numeral 17.

It is believed that the many advantages of a 100 fire extinguisher constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed. 105

What is claimed is:—

1. In combination with an enclosure including 110

- a door, a fire extinguisher comprising a cylinder containing a fire extinguishing fluid under pressure, fluid discharge means in the enclosure and communicating with the cylinder for receiving fluid therefrom, a fluid actuated piston in the cylinder controlling the flow of the fluid to the discharge means, and means operatively connecting the door to the piston for actuation to closed position thereby.
- 10 2. In combination with an enclosure including a door, a fire extinguisher comprising a cylinder containing a fire extinguishing fluid under pres-

sure, fluid discharge means in the enclosure and communicating with the cylinder for receiving fluid therefrom, a fluid actuated piston in the cylinder controlling the flow of the fluid to the discharge means, and means operatively connecting the door to the piston for actuation to closed position thereby, the last-named means including a cam fixed to the door, a rod extending slidably into the cylinder and connected to the piston, and a roller journaled on the rod and operatively engaged with the cam. 80 85
